[57] CLAIM

The ornamental design for an ink ribbon holder, as shown and described.

DESCRIPTION

FIG. 1 is a top, rear and left side perspective view of an ink ribbon holder showing our new design;

FIG. 2 is a top view, looking down on the ink ribbon holder;

FIG. 3 is a bottom view looking up of the ink ribbon holder;

FIG. 4 is a left-hand side view of the ink ribbon holder;

FIG. 5 is a right-hand side view of the ink ribbon holder;

FIG. 6 is a front view of the ink ribbon holder; and,

FIG. 7 is a rear elevational view of the ink ribbon holder.
